(57) **CLAIM**

The ornamental design for a throwing apparatus, as shown and described.

DESCRIPTION

FIG. 1 is a front perspective view of a throwing apparatus in accordance with our new design;

FIG. 2 is a side perspective view thereof;

FIG. 3 is a side perspective view thereof;

FIG. 4 is a bottom view thereof;

FIG. 5 is a top view thereof;

FIG. 6 is a side view thereof;

FIG. 7 is a side view thereof;

FIG. 8 is a back view thereof; and,

FIG. 9 is a front view thereof.

The broken lines depict environmental subject matter, are for illustration only, and form no part of the claimed design.
